UNITED STATES PATENT OFFICE.

CHARLIE C. PLUMER, OF CONCORD, NEW HAMPSHIRE.

GARMENT.

1,280,537.

Specification of Letters Patent.

Patented Oct. 1, 1918.

Application filed February 27, 1914. Serial No. 821,468.

To all whom it may concern:

Be it known that I, CHARLIE C. PLUMER, a citizen of the United States, residing at Concord, in the county of Merrimack and 5 State of New Hampshire, have invented new and useful Improvements in Garments, of which the following is a specification.

This invention relates to garments and more particularly to what has heretofore 10 been known as "broadfall" trousers.

The principal object in this type of trousers is of course to produce a garment which may be more readily applied and removed than the usual construction embodying a 15 front fly.

Another object of the invention is to provide novel side connections and to produce a flap capable of carrying a side pocket.

Further objects of the invention will appear as the following description is read in connection with the accompanying drawing, which forms a part of this application, and in which:—

Figure 1 is a front elevation showing a 25 portion of the fall or front of the trousers turned back to show one of the pockets.

Fig. 2 is a detail horizontal section taken on the line 2—2 of Fig. 1.

In the specific embodiment of the invention as illustrated herein the trousers are 30 formed of front leg portion 1, 2 and back leg portion 3, 4, stitched together in the usual form of broadfall trousers, *i. e.*, having the inside leg seams continued through- 35 out the crotch to the waist-band in both front and the rear, as will be readily understood. The side seams terminate consider- ably short of the waist-band 5 and both 40 front and back portions are hemmed and properly felled to prevent ragged edges.

Attached to the marginal side edges of the rear pieces 3 and 4 are flaps 6 slitted vertically as shown at 8, to provide an entrance into the pockets 7 which are stitched 45 thereto around the slits. The fall 9 is formed by that portion of the two front pieces 1 and 2 above the upper ends 16 of said side seams which, as shown, terminate opposite the lower ends of the pocket-slits 8. 50 The side edges of the fall rise vertically from the points 16 to substantially square corners at the line of the front section of the waist band 5, and this section is attached to the upper edge of the flaps by hooks and 55 eyes 10 or in any other suitable manner. On the outside of the waist-band are belt loops 110

17, and the inner side of the flaps have secured thereto the suspender buttons 11 which connect with the front tabs of the 60 suspenders so that in removing the trousers it is not necessary to disconnect the suspend- ers each time.

If desirable, the fall may be provided with a blind fly and may have a watch 65 pocket such as is shown at 12 constructed in the fall.

The flaps 6 are extended at the waist line by strips 13 joined together at their terminal ends by a hook 14 or any other suitable manner. Thus it will be seen that the 70 trousers will be properly supported even when the fall is lowered and without the aid of suspenders. These flaps may be omitted or left unhooked where suspenders are used and the suspender buttons may be omitted 75 where a belt is employed and the trousers are used as hip trousers.

It will be seen that the pockets are supported entirely from the flaps, and the latter from the waist line whether the strips 80 are hooked together or not and whether the garment is supported by suspenders or a belt. The entrance to each pocket is through a slit which I preferably make vertical as shown, but in any event it is cov- 85 ered by the corner of the broad fall when in place as seen at the left of Fig. 1. There- fore loss of objects from the pockets is rendered less liable, while permitting the wearer to insert his hands therein by pass- 90 ing them under the edges of the fall. The latter also is of such breadth that extraneous objects will not accidentally drop into the mouths of the pockets when covered by the fall, and the fact that the upper edge of the 95 fall reaches to the waist line prevents drip- ping water or grease from getting inside the garment while the wearer is at work. If his waist line should increase or decrease dur- 100 ing the life of this garment, he can readily fit it to him by adjusting the connection be- tween the meeting ends of the strips 13 and possibly also the position of the eyes 10 on the flaps 6 where the corner hooks on the fall engage them. The presence of an addi- 105 tional pair of hooks and eyes between the fall and the inner edges of the flaps 6, avoids the absolute necessity for connecting the inner extremities of the strips 13 at all times, especially as these strips are covered by the 110 waist line of the fall under ordinary conditions. Even suppose that the wearer should

become quite corpulent during the life of this pair of trousers, it yet might be adapted to him by opening the side seams and letting out the material. This possibility flows 5 from the fact that the pockets are set into slits in the flaps 6 and not in the side seams which may therefore be adjusted without interfering with the pockets.

What is claimed is:—

- 10 The herein described garment comprising a pair of rear leg pieces making up the rear portion, a pair of front pieces making up the front portion, lines of stitching connecting the inner edges of the rear and front 15 pieces to the crotch and upward in each portion above the same, other lines of stitching connecting the outer edges of the front and rear pieces to points considerably below the waist-band, the front portion being free 20 above said point to constitute a broad fall substantially right-angular at its upper end,

belt-loops on the waist line of both portions, flaps connected with the side edges of the rear pieces and having vertical slits, front pockets whose mouths are united to the flap 25 around such slits, strips attached to the free edges of the flaps at the front waist line and having means for detachably connecting their inner ends, suspender buttons inside the waist-line at the upper ends of said flaps, 30 and detachable fastening devices inside the waist line of the fall and outside the waist line of the flaps whereby the side edges of the fall cover the slits when its corners are fastened. 35

In testimony whereof I affix my signature in presence of two witnesses.

CHARLIE C. PLUMER.
